CLAIM

The ornamental design for a circuit breaker with a front panel, as shown and described.

DESCRIPTION

FIG. 1 is a front, side perspective view of a circuit breaker with a front panel showing our design;

FIG. 2 is a front, side perspective, exploded view of the circuit breaker with a front panel shown in FIG. 1;

FIG. 3 is a front view of the circuit breaker with a front panel shown in FIG. 1;

FIG. 4 is a top view of the circuit breaker with a front panel shown in FIG. 1;

FIG. 5 is a bottom view of the circuit breaker with a front panel shown in FIG. 1;

FIG. 6 is a side view of the circuit breaker with a front panel shown in FIG. 1;

FIG. 7 is an opposing side view of the circuit breaker with a front panel shown in FIG. 6;

FIG. 8 is a front, side perspective view of another embodiment, illustrating a circuit breaker with a front panel showing our design;

FIG. 9 is a front, side perspective, exploded view of the circuit breaker with a front panel shown in FIG. 8;

FIG. 10 is a front view of the circuit breaker with a front panel shown in FIG. 8;

FIG. 11 is a top view of the circuit breaker with a front panel shown in FIG. 8;

FIG. 12 is a bottom view of the circuit breaker with a front panel shown in FIG. 8;

FIG. 13 is a side view of the circuit breaker with a front panel shown in FIG. 8; and,

FIG. 14 is an opposing side view of the circuit breaker with a front panel shown in FIG. 13.

The broken line portions of the drawings is included to show portions of the article that form no part of the claimed design.

1 Claim, 12 Drawing Sheets
